UNITED STATES PATENT OFFICE

DAVID S. JACOBUS, OF MONTCLAIR, NEW JERSEY, ASSIGNOR TO THE BABCOCK & WILCOX COMPANY, OF BAYONNE, NEW JERSEY, A CORPORATION OF NEW JERSEY

STEAM BOILER

Application filed August 25, 1927. Serial No. 215,301.

This invention relates to steam boilers of the water tube type that are suitable for high pressures, and will be understood from the description in connection with the accompanying drawings, in which Fig. 1 is a vertical section through an embodiment of the invention; Fig. 2 is a section along the line 2—2 of Fig. 1; Fig. 3 is a section along the line 3—3 of Fig. 1 and Fig. 4 is a section along the line 4—4 of Fig. 1.

In the drawings, reference character 5 indicates inclined water tubes that may be installed, for example, above a furnace, so that the hot products of combustion can pass across the same. These tubes are connected to headers 6 and 7 at the respective ends thereof, and baffles 8, 9, 10 and 11 are provided to cause the hot products of combustion to traverse the tubes 5, with three passes thereacross, as indicated by the arrows. A partition or baffle 12 is provided to direct the waste gases to the outlet 13.

Nipples 15 connect the upper ends of the headers 6 to the lower portion of inclined tubular headers 16 that extend longitudinally of the boiler, and are shielded from the hot products of combustion by means of the baffles 10 and 12. Nipples 17 connect the upper ends of the headers 7 to the upper portions of the headers 16. These tubes cross each other, as indicated most clearly in Fig. 2, so that water will circulate between the headers to prevent too much concentration of impurities in any particular headers and rows of tubes. Supporting straps 18 may extend from supports 19 under the headers 16. A cross pipe 20 for feed water extends across the boiler beneath the headers 16, and is connected to these headers by means of the tubes 21, and is suspended from the headers by means of the straps 22.

Nipples 24 connect the lower ends of the header 16 to vertically disposed headers 25. The upper ends of the headers 25 are connected by means of nipples 26 to the cross pipe 27, and tubes 28 connect the cross pipe 27 to a parallel cross pipe 29, the ends of which are provided with connections 30 for pipes to a steam main.

The upper ends of the headers 16 are con-

nected by means of tubes 31 to the upper portions of the vertically-disposed headers 25.

The operation is as follows: Feed water is fed in any convenient manner through the cross pipe 20, from which it enters the headers 16 through the pipes 21, and flows downwardly through the nipples 15, downtake headers 6, through the tubes 5, where steam is generated. The mixture of steam and water flows upwardly through the headers 7, nipples 17, into the headers 16, where the steam and water is separated, the water flowing downwardly in the headers 16 and the steam passing through the tubes 31 to headers 25, where more separation of steam and water may take place, the water flowing downwardly through the nipples 24 into the headers 16, and the steam passing upwardly into the cross pipe 27, and thence through the tubes 28 to the cross pipe 29 and out through the connections 30 to the steam main.

The water level will preferably be maintained at a point where the headers 16 will be about half full of water, and a mud drum 32 of the usual sort is located below the headers 6 and is provided with a blow-off pipe in the usual manner.

I claim:

1. In a water tube boiler, vertically disposed headers, inclined tubes connected to said headers, inclined headers, connections from said vertically disposed headers to said inclined headers, and vertically disposed headers located above said inclined headers and connected to the respective end portions of said inclined headers out of line with said first named connections.

2. In a water tube boiler, vertically disposed headers, inclined tubes connected to said headers, inclined headers located above said headers, connections from said vertically disposed headers to said inclined headers, and vertically disposed headers located above said inclined headers and connected to the respective end portions of said inclined headers out of line with said first named connections.

3. In a water tube boiler, vertically disposed headers, inclined tubes connected to

said headers, inclined headers, connections from said vertically disposed headers to said inclined headers, vertically disposed headers located above said inclined headers and connected to the respective end portions of said inclined headers out of line with said first named connections and means for feeding water to said inclined headers.

4. In a water tube boiler, inclined tubes connected at their ends to vertically extending headers, horizontally inclined headers above said tubes and said vertically extending headers in which separation of steam and water takes place, connections from the uppermost ends of said vertically extending headers to points adjacent the ends of said horizontally inclined headers, vertically disposed headers above the lowermost ends of said horizontally inclined headers, in which separation of steam and water also takes place, tubes connecting the uppermost ends of said horizontally inclined headers, to said last named vertically disposed headers, connections from the lowermost ends of said last named vertically disposed headers to the lowermost ends of said horizontally inclined headers and a common steam outlet to which said last named vertically disposed headers are connected.

DAVID S. JACOBUS.
